US0D1097928S

(12) **United States Design Patent** (10) **Patent No.:** **US D1,097,928 S**
(45) **Date of Patent:** **** Oct. 14, 2025**

(54) **VEHICLE PEDAL**

(71) Applicants: **Rivian IP Holdings, LLC**, Plymouth, MI (US); **Amazon Technologies, Inc.**, Seattle, WA (US)

(72) Inventors: **Matthew Braun**, Ann Arbor, MI (US); **Zulfiqar Ali**, West Bloomfield, MI (US)

(73) Assignees: **Rivian IP Holdings, LLC**, Plymouth, MI (US); **Amazon Technologies, Inc.**, Seattle, WA (US)

(**) Term: **15 Years**

(21) Appl. No.: **30/001,909**

(22) Filed: **Apr. 30, 2025**

Related U.S. Application Data

(60) Continuation of application No. 29/891,557, filed on May 8, 2023, now Pat. No. Des. 1,077,698, which is a continuation of application No. 29/843,139, filed on Jun. 17, 2022, now Pat. No. Des. 989,675, which is a division of application No. 29/757,125, filed on Nov. 3, 2020, now Pat. No. Des. 957,294.

CLAIM

The ornamental design for a vehicle pedal as shown and described.

DESCRIPTION

FIG. 1 is a front view of a vehicle pedal showing the claimed design;

FIG. 2 is a top view of the vehicle pedal;

FIG. 3 is a bottom view of the vehicle pedal;

FIG. 4 is an upper front left corner perspective view of the vehicle pedal; and,

FIG. 5 is a lower front right corner perspective view of the vehicle pedal.

The broken lines depict portions of the vehicle pedal that form no part of the claimed design.

1 Claim, 4 Drawing Sheets
